US00D985945S

(12) **United States Design Patent** (10) **Patent No.:** **US D985,945 S**
(45) **Date of Patent:** **** May 16, 2023**

(54) **ORAL CARE IMPLEMENT HANDLE**

(71) Applicant: **Colgate-Palmolive Company**, New York, NY (US)
(72) Inventors: **John Gatzemeyer**, Hillsborough, NJ (US); **Oliver William Henderson**, Brooklyn, NY (US); **Scott Vincent Pancioli**, San Francisco, CA (US); **Norio Fujikawa**, San Francisco, CA (US)

(73) Assignee: **Colgate-Palmolive Company**, New York, NY (US)

(**) Term: **15 Years**

(21) Appl. No.: **29/833,889**

(22) Filed: **Apr. 7, 2022**

CLAIM

The ornamental design for an oral care implement handle, as shown and described.

DESCRIPTION

FIG. 1 is a front perspective view of an oral care implement handle showing the new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof; and,

FIG. 8 is an enlarged bottom view thereof.

The broken lines illustrate portions of the oral care implement handle that form no part of the claimed design.

1 Claim, 5 Drawing Sheets
